WOODWORKING MACHINE

Oscar George Day, Ridgewood, N. Y., assignor to
New York Progressive Wood Heel Corporation,
Brooklyn, N. Y., a corporation of New York

Application May 10, 1940, Serial No. 334,335

2 Claims. (Cl. 144—144)

The present invention relates to improvements in wood-working machines, and relates more particularly to an improved machine for shaping heels.

The main object of my invention is to provide a machine which will shape the upper face of a heel, and more particularly the upper face of a wedge type heel.

The shaping of the top surface of a wedge type heel is presently accomplished by a turning machine in which the heel is placed in a clamping member and manually moved into contact with a set of revolving cutting blades. When the heel surface has been cut, the clamp member is manually loosened, the finished heel removed, and a new blank inserted. This process is both slow and tedious.

Therefore, another object of my invention is to provide a machine which will automatically grip a heel, shape the upper surface thereof and thereafter release said heel.

Presently, the top surface of a wedge type heel is a single curved surface, not allowing for the differences in depth which should be present between the inner edge of the top surface and the outer edge thereof. It is of great advantage that a wedge type heel have the edge correspond to the arch of the foot, so the top surface of the front part of the heel will more closely accommodate the base of the foot.

Therefore, another object of my invention is to provide a machine which will cut a warped surface on the top face of a wedge type heel, said surface being shaped to accommodate the base of the human foot.

Another object of my invention is to provide a machine which will automatically grip a blank, cut a predetermined warped surface in the top face of said blank and thereafter release said blank.

Still another object of my invention is to provide a machine which will automatically grasp a blank wedge type heel whose sides have been cut to shape, cut a predetermined warped concave surface in the top face of said blank and thereafter release the shaped heel.

Other objects of my invention will be set forth in the following description and drawings which illustrate a preferred embodiment thereof, it being understood that the above statement of the objects of my invention is intended generally to explain the same without limiting it in any manner.

Figure 1 is a side elevation of my complete heel cutting machine;

Figure 2 is a section along line 2—2 of Figure 1;

Figure 3 is a section along the line 3—3 of Figure 2;

Figure 4 is a section along line 4—4 of Figure 2;

Figure 5 is a detail view of the motor frame universal joint;

Figure 6 is a section along line 6—6 of Figure 10 5;

Figure 7 is a section along line 7—7 of Figure 4;

Figure 8 is a fragmentary top plan view of another embodiment of work holding jaws;

15 Figure 9 is a front view of Figure 8, the jaws being shown partially in section;

Figure 10 is a perspective view of one type of cut piece; and

Figure 11 is a perspective view of another type of cut piece.

Referring to the drawings, A designates a bench frame, said bench frame having all the working parts of my machine positioned thereon. Extending upward at one end of the bench frame A is the vertical frame standard 1 having a universal joint B positioned on the upper face thereof, said joint universally securing the motor frame C to said standard 1.

Referring to Figures 5 and 6, the universal 20 joint B comprises a bearing member 10 secured to the top wall 2 of the frame standard 1 by means of a pair of bolts 3 passing through flanges 11 extending sidewardly from said bearing member 10 and through said top wall 2. Pin 12 is

35 rotationally positioned in bearing 10 and terminates in a pin receiving member 13 having the axis of bore 14 of said pin receiving member 13 normal to the axis of pin 12. Rotationally secured to member 13 by means of pin 15 and lock nut 16, said pin passing through openings in the extensions 17 of the motor holding frame C and the bore 14, is the motor holding frame C.

Positioned on the frame C is motor D, said motor D being secured to the frame by means of 45 a pair of bolts 4 passing through said frame and the base of said motor. Projecting downwardly from the free end of the motor holding frame C are flanges 20, said flanges acting as bearings for the knife holding shaft 21, said knife holding 50 shaft passing completely through one of said flanges and having a pulley 22 rotationally rigid therewith, said pulley being fixed on that part of the shaft which passes through the flange 20. A belt 23 connects pulley 21 with the pulley 22

55 fixed to the drive shaft of the electric motor D.

Also rotationally rigid with said knife shaft 21 are the cutting knives 24 which may assume any shape, depending upon the surface of the finished heel desired.

Depending from the flanges 20 are the roller bearing members 25 having the concave face wheels 26 rotationally held between the vertical arms 27 of said member 25 by means of pins 28. A forced draft suction hood 29 is provided above the cutting knives 24 so as to draw off any shavings or cuttings from the remainder of the mechanism.

The bench frame member A comprises a lower base 30 and an upper base 31. Positioned on the lower base 30 is the motor M and the reduction gear box G. The reduction gear box is of any known type, the one shown being of the worm and gear type.

The universal coupling member 32 secures the drive shaft 33 of the motor M to the high speed shaft 34 of the reduction gear box G.

Positioned on one side 35 of the upper base 31 of the bench frame A are the bearing members 41 having shaft 42 rotationally held therein, said shaft 42 having a pulley 43 shown in broken line, and an eccentric wheel 40 fixed thereon. The eccentric wheel 40 has a diametric slot 46 formed therein, said eccentric wheel 40 having an adjustable connecting rod 47 connected thereto by means of a pin 48 passing through one end of the connecting rod and through slot 46, said pin 48 being adjustable within said slot 46.

The adjustable connecting rod 47 is formed of two parts 48' and 49 having corresponding longitudinal slots 50 and 51 formed therein and being connected by a pair of bolts 52, said bolts passing each inner end of parts 48 and 49 and the adjoining slot thereto. The other end of said connecting rod 47 is connected to the carriage member E.

A pair of parallel tracks 60 of circular cross section extends from the front of the bench member just above the top base thereof to a point substantially in the middle of said base member. Another track member 61 also runs from the front of the bench parallel to the tracks 60 and terminating at about the same point as the tracks 60, said track 61, however, being situated at a higher elevation than track 60, and having a depressed portion 62 at a point substantially close to the initial point of said track. The carriage member E is connected to the connecting rod 47 by means of a pin bolt 63 passing through a bifurcated eye flange 64, said eye flange extending rearwardly of said carriage E and said bolt also passing through an aperture of the forward end of the said connecting rod 47.

The carriage E has a pair of longitudinal parallel bores 65 formed therein, said bores being slidably engaged by the parallel track members 60 and said carriage being adapted to freely ride on said tracks.

A work holding member F is adjustably fixed on the carriage E by any suitable means.

In the present case, an intermediate plate 66 is pivotally mounted around bolt 67, said bolt passing through an opening 68 of said plate 66 and being fixed in the inner vertical flange wall 69 of the carriage E.

An arcuate T-shaped slot 70 is formed in said intermediate plate 66, the center of curvature of said slot being the center of the opening 68, said slot 70 having shoulders 70a formed therein. A bolt 71 having the inner face of the head 71a resting on the shoulders 70a passes through said

slot 70 and aperture 70b formed in flange 69 said bolt 71 having nut 71b engaging its free end and being adapted to fixedly set plate 66 to flange 69. Mounted in said plate 66 and being vertically adjustable in said plate, is the work holding member F, said work holding member F having a depending flange 72 slidably mounted in a groove 73 formed on the right face of the plate 66. A vertical slot 72a is formed in the flange 72 said vertical slot having passing therethrough the bolt 67 which bolt has the washer 67a at its headed end pressing against the outer face of flange 72. The vertical position of work holding member A may thus be fixed by said bolt 67.

The aforescribed arrangement allows the work holding member to be adjustable as to the angle it makes to the horizontal and also adjustable in a vertical movement.

The work grasping member comprises a pair of jaws 80 and 81, one of said jaws being substantially stationary and the other of said jaws being movable so as to allow for the insertion or removal of the work piece.

The stationary jaw 80 comprises the jaw member proper 82 having a horizontal normal projection 83, said projection 83 being slidable within an aperture formed in a block 85, said block 85 being positioned on the left hand top face of the work holding member F. A pair of stiff compression springs 86 are housed in openings 85' in the block 85 and press against the inner faces of depressions formed in the inner side of the jaw 82.

The movable jaw member 81 is positioned on the vertical leg of angle member 87 by means of bolt 88, the horizontal leg of said angle member being secured to the slidable member 89, said slidable member having a rod 90 of rectangular cross section slidably mounted within the corresponding groove 91 formed within the upper part of member 92 of the work holding member F.

At the outer right end of said slidable member 89 is positioned the roller member 93, said roller member being held between the projecting pair of arms 94 by means of pin 95.

A tension spring 96 having one end fixed to any convenient point 97 of the work holding member F and having its other end secured to the free end of the rod 90 outwardly impels the said rod 90 whereby the roller 93 is in contact with the working face of the track 61, thus keeping the jaws 80 and 81 in open position when said roller contacts the depressed portion of said track. On the other hand, when the carriage E is further forward and the roller 93 is in contact with the raised portion of track 61 the jaws 80 and 81 assume a closed position.

A work holding base 100 and a work holding front 101 having the adjustable set screw 102 is also provided on said work holding member so as to conveniently position the work piece.

Removably secured to the outer side of vertical flanges 103 of the carriage E by means of bolts 104 passing through the said vertical flanges 103 and nuts 105, are the pair of guide members 106, said guide members having an upper cam edge 107. The shape of this cam edge depends upon the desired shape of the upper surface of the heel and it should be noted that if a warped surface is required the shape of the upper cam edge of each of the guide members is different. The wheels 26 and the guide members 106 are so positioned that the concave surface of the wheels 26 ride on the cam edges of said guide members.

On the left leg 39 of the bench member is provided adjustable belt tautening means 108 having a roller 109 contacting the belt 110.

My device operates as follows:

The work holding member F is adjusted to the desired position by means of the adjusting mechanism consisting of the plates 66, 69 and 72. The motors D and M are caused to operate, thus revolving the cutting knives 24 and the eccentric wheel 40 which in turn causes the carriage member E to reciprocate. When the carriage member E is at its rightmost position, the roller 93 of the movable jaw member is impelled into the depression 62 of the track member 61 by spring 96, thus opening the work grasping jaw members and allowing the work piece blank to be inserted therebetween.

The work piece blank is then inserted and the carriage member E moves towards the left, the roller 93 of the movable jaw being caused to ride out of the depression 62, and bringing the work holding jaws into closed position, thus grasping the blank. While the blank is thus grasped between the jaws, the carriage is moved so that said blank is brought into contact with the revolving knives 24 and the upper surface of said blank is cut to the shape predetermined by the contour of the cam edge of the guide members 106, the knives 24 being controlled through the rollers 26 rolling along said cam edge. After the blank has passed the revolving knives and reached the leftmost position of the reciprocating stroke, the direction is reversed since the eccentric wheel has completed half a revolution, and the carriage is then returned to the rightmost position, whereat the roller 93 again falls into the depression 62, thus causing the work holding jaws to separate and allowing the finished heel to be removed from the work holding member and the new heel therein inserted.

I have shown the gripping surface of the work grasping jaws as being flat and the revolving knives being so shaped as to cut a surface whose transverse elements are straight lines. However, as shown in Figures 8 and 9, the work gripping surfaces 110 and 111 of the jaws may be of arcuate shape so as to engage a heel whose sides have

already been shaped, and the knives 112 may be curved so as to cut a surface in the upper part of the heel whose transverse elements are concave.

5 Figure 10 shows a finished work piece as cut by a straight knife and as engaged by the plane surface jaws, whereas Figure 11 illustrates a heel in which the sides have been shaped before being inserted into the machine, and in which the 10 curved knives have been employed.

I have shown preferred embodiments of my invention but it is obvious that numerous alterations and omissions may be made without departing from its spirit provided they come within 15 the scope of the claims.

I claim:

1. A machine of the character described comprising a base portion, a standard mounted at one end of said base portion, a motor holding 20 frame, one end of said motor holding frame being universally connected to the top end of the standard, an electric motor mounted on said motor holding frame, revolving cutting means depending from the free end of said motor holding frame and being motivated by the said electric motor, guide rollers fixed relative to said cutting means, horizontal track members mounted on said base portion normal to the axis of rotation of said cutting means, a carriage slidable along 25 said tracks, means for reciprocating said carriage, a work holding member mounted on said carriage, a pair of guide members positioned on said carriage and having upper cam surfaces of different contours, said guide members being positioned 30 on either side of said work holding member and being substantially spaced therefrom, said cam surfaces running in a direction parallel to the direction of movement of said carriage, said cam surfaces engaging said guide rollers thereby determining the position of the cutting member 35 relative to the piece positioned in the adjustably mounted work holding member.

2. A machine as characterized in claim 1 in which the work holding member is adjustable 40 vertically and angularly with respect to the slidable carriage.

OSCAR GEORGE DAY.
